UNITED STATES PATENT OFFICE

161,986

LINOTYPE CARTRIDGE STAND

Harry F. Worsley, Washington, D. C.

Application August 30, 1948, Serial No. 148,370

Term of patent 3½ years

(Cl. D80—9)

To all whom it may concern:

Be it known, that I, Harry F. Worsley, a citizen of the United States, residing in the city of Washington, District of Columbia, have invented a new, original, and ornamental Design for Linotype Cartridge Stand, of which the following is a specification, reference being had to the accompanying drawing, forming part thereof, wherein:

Figure 1 is a front elevational view of a linotype cartridge stand showing my new design;

Figure 2 is a side view of the stand; and

Figure 3 is a top or plan view of the stand.

I claim:

The ornamental design for a linotype cartridge stand, substantially as shown.

HARRY F. WORSLEY.
